POWER CONVERTER

Donald J. Gnaedinger and Melvin F. Walter, Highland,
Ill., assignors to Basler Electric Company, Highland, Ill.

Filed Aug. 29, 1969, Ser. No. 18,913

Term of patent 14 years

Int. Cl. D13—02

U.S. Cl. D26—15

FIG. 1

FIG. 4

FIG. 2

FIG. 5

FIG. 3

FIG.6

FIG. 1 is a top plan view of a power converter, showing our new design;

FIGS. 2 and 3 are end elevations thereof;

FIG. 4 is a side elevation;

FIG. 5 is a bottom plan view; and

FIG. 6 is a perspective view of the converter.

The undisclosed side is substantially the same in appearance as the side shown.

We claim:

The ornamental design for a power converter, substantially as shown and described.
